UNITED STATES PATENT OFFICE.

THOMAS F. HATHAWAY, OF ELGIN, ILLINOIS, ASSIGNOR TO ILLINOIS WATCH CASE COMPANY, OF ELGIN, ILLINOIS, A CORPORATION OF ILLINOIS.

ATTACHMENT FOR WRIST-WATCHES.

1,162,480.

Specification of Letters Patent. Patented Nov. 30, 1915.

Application filed May 24, 1915. Serial No. 30,241.

To all whom it may concern:

Be it known that I, THOMAS F. HATHAWAY, a citizen of the United States, residing at Elgin, in the county of Kane and State 5 of Illinois, have invented certain new and useful Improvements in Attachments for Wrist-Watches, of which the following is a specification.

The present invention relates to an attachment or device for use in connection with 10 wrist watches which enables the watch to be turned while upon the wearer to expose either the face or back as desired.

One of the objects of the invention is to 15 provide means for attaching in a simple and efficient manner by a swivel connection to a watch body both ends of a chain or bracelet.

A further object is to provide means for 20 effecting swivel connections between the ends of a chain or bracelet and the watch body, which means are capable of being applied to the watch body in a manner whereby no openings or holes in the watch case 25 are necessitated other than those usually and ordinarily provided.

A further object of the invention is to 30 configure the parts attached to the watch body so that they are of a symmetrical nature and possess an attractive appearance when applied to the watch body.

A further object of the invention is to 35 arrange these connections so that if the chain or bracelet is removed and the watch worn as a chatelaine or belt it will not possess an appearance which would identify it as a 40 wrist watch that was being used in a different manner than intended.

A further object of the invention is to 45 arrange and construct the parts which are attached to the watch body whereby they are strong and durable and not liable to become broken or separated from the body of the watch by a striking of the same against a surface.

The invention further consists in the features of construction and combinations of parts hereinafter described and claimed.

In the drawings: Figure 1 is an elevation 50 showing a wrist watch with the attachment of the present invention applied thereto and the chain or bracelet attached; Fig. 2 is an enlarged detail showing a plan view of the secondary swivel attachment; Fig. 3 is an enlarged sectional detail through a portion 55 of the watch body and the secondary swivel

attachment; and Fig. 4 is a detail section taken at right angles to the section shown in Fig. 3 showing a portion of the watch body and the secondary swivel attachment.

In the art to which the present invention 60 relates, it is desirable to provide these wrist watches with a means for swivelly attaching both ends of the chain or bracelet to the body of the watch for the purpose of permitting the watch to be turned while on the 65 wearer so as to expose either the face or back as desired, since the backs are frequently made in a highly ornamental manner and create a very attractive appearance when exposed, and moreover when the back is exposed 70 the danger of breaking the crystal by striking against a surface is eliminated. It is, of course, necessary to turn the watch so as to expose the face when it is desired to 75 read the time. It is, moreover, desirable to so construct the watch body as to permit the watch to be used as either a chatelaine or 80 wrist type of watch as desired, and, therefore, the means permitting the swivel connection between the ends of the chain or 85 bracelet and the body of the watch should be of a character so that they lend an attractive appearance to the watch case when the watch is used as a chatelaine type of watch.

Referring now to the drawings, and particularly to Fig. 1, the device is shown as applied to a wrist watch 5 of any suitable style or character. This watch is provided with a pendant 6 carrying a bow 7, and this pendant is of the swivel variety; that is it 90 can freely turn about the stem of the watch, and for clearness in description this pendant and bow may be termed the primary swivel connection to the watch body. Placed opposite this primary swivel connection is a 95 secondary swivel connection designated generally by the numeral 8. It is, of course, understood that these terms primary and secondary are simply used for expediting the description and are not meant as terms 100 of limitation since so far as swiveling is concerned one connection is just as important as the other.

The bracelet 9, which is used in the drawings for illustrative purposes, is of the usual 105 expansion link type and may be of any form or design desired.

The secondary swivel connection, which forms the subject matter of the present invention consists of a body 10 formed of two 110

outwardly extending arms 11 and a central portion 12 raised or elevated with respect to the arms as will be apparent from Figs. 1 and 4. The arms 11 are each formed with an inner curvilinear face 13 which is curved in conformity to the outer periphery of the watch case, and as will be seen from the drawing provides a substantially long surface so that the member 8 can be substantially and easily soldered or otherwise affixed to the watch body. The outer face 14 of each of the arms 11 is of a concavo-convex formation, and these faces terminate at their inner ends in curvilinear raised shoulders 15.

A ring post 16 is swivelly mounted in the central portion 12 of the member 10 and the inner end of this ring is chambered as at 17 so as to permit a ready and easy upsetting of this inner end of the post to provide flanges 18 which hold the post in place, although permitting a ready turning of the post within the portion 12.

As will be seen from Fig. 4, the curvilinear shoulders 15 extend up a substantial distance about the ring portion 19 of the post. By so constituting the shoulders two important results are obtained. First, a guard or protection is placed around this ring which tends to deflect from the ring any blow occasioned by the striking of the watch against a surface. This is material since the ring must necessarily be of a small and delicate nature whereby it could not withstand the shock or jar of a blow. Secondly, by so arranging the shoulders 15, with respect to the ring, an attachment is provided at the bottom of the watch which is symmetrical in nature forming sort of a scroll work and thus when the watch is used as a chatelaine or belt type it is of an attractive appearance, the secondary or swivel connection partaking of the characteristics of an ornament on the bottom 45 of the watch. By attaching the ring post in the manner described no boring or puncturing of the watch case is necessary, and this is important since if it is necessary to bore through the watch case the hole thus 50 made will be liable to permit ingress of dirt into the interior of the case, which obviously is highly undesirable. By use of the foregoing invention the secondary swivel attachment can be readily and quickly placed

upon the watch body without boring or 55 otherwise cutting away the case, and the primary swivel attachment is a portion of the necessary parts of a watch.

I claim:

1. An attachment for wrist watches comprising a body portion formed with oppositely extending arms each having an inner face configured in conformity to the configuration of the periphery of a watch case and adapted to be secured thereto, a 65 central portion intermediate said arms and a ring swiveled in said central portion, substantially as described.

2. An attachment for wrist watches comprising a body portion composed of oppositely extending arms having their inner faces configured in conformity to the configuration of the periphery of a watch case and adapted to be secured to said periphery, a central portion intermediate said arms, a 75 ring swivelly mounted in said central portion and shoulders on the adjacent ends of said arms extending outwardly and partially embracing said ring, substantially as 80 described.

3. As a new article of manufacture, an attachment for wrist watches comprising a body formed with oppositely extending arms having their inner faces configured in conformity to the configuration of the periphery of a watch case and adapted to be secured to said periphery, a central portion intermediate said arms and lying above the inner faces of the arms, substantially as 85 described.

4. As a new article of manufacture, an attachment for wrist watches comprising a body formed of oppositely extending arms having their inner faces configured in conformity to the configuration of the periphery of a watch case and adapted to be secured to said periphery, a central portion, the inner face of the central portion lying above the lower faces of the arm portions and projections extending from the adjacent ends of the arms and projecting above the central portion, substantially as 90 described.

THOMAS F. HATHAWAY.
